UNITED STATES PATENT OFFICE.

CHARLES R. MABEE, OF TOLEDO, OHIO.

EVAPORATING APPARATUS.

1,420,645.

Specification of Letters Patent. Patented June 27, 1922.

Original application filed October 23, 1913, Serial No. 797,087. Renewed July 12, 1916, Serial No. 108,956. Divided and this application filed December 9, 1913. Serial No. 805,598.

To all whom it may concern:

Be it known that I, CHARLES R. MABEE, citizen of the United States, residing at Toledo, in the county of Lucas and State of Ohio, have invented certain new and useful Improvements in Evaporating Apparatus, of which the following is a specification, reference being had therein to the accompanying drawing.

This invention relates to an improved evaporating apparatus, and more particularly to an apparatus wherein the substance to be treated or evaporated will, by the operation of the apparatus, be conveyed and maintained in active proximity relative to a treating surface under pressure, toward and movable across or over the treating surface.

Various types of apparatus have heretofore been employed for treating substances for evaporating the water therefrom, either to reduce the material to a solid, powder, or dried state, or to a concentrated or semi-liquid state, a common form of apparatus comprising a suitably heated container for the substance, and means within the container for constantly stirring the material, whereby the same, by the stirring action, continuously moves toward and from the surface.

It has also been suggested to employ open evaporating pans, with means for heating the contained liquid.

Apparatus of the character above stated have proven unsuccessful to a large extent because expensive and because the long period required for the treatment had an objectionable and injurious effect upon the material being treated.

Again, it has heretofore been proposed to utilize vacuum pans or apparatus, it having been recognized that the addition of pressure to the liquid would impede the evaporation. It has been ascertained, however, from the operation of the improved apparatus, presently to be described, that by the provision of means for treating the material under pressure, preferably centrifugal force, and maintaining the material under constant movement, or advancement over the heated surface, better, more economical and expeditious results are obtained than is possible with prior apparatus for the same purpose.

More particularly, the invention includes means whereby a relatively shallow body of

material in liquid form, or containing liquid, is maintained and subjected, while under gyratory motion, in a circular path, through the action of centrifugal force, which carries and holds the same in contact or in proximity to a surface having a temperature differing from that of the material to be treated, and at the same time, retaining a free space into which the generated vapors or gases readily pass and escape or are abstracted.

Other and further improvements and novel details in the construction and arrangement of parts will be more particularly brought out in the description to follow, it being understood in this particular, however, that many obvious changes in the details of construction and arrangement of parts may be made without departing from the principle or spirit of the invention.

The specification is to be considered in connection with the accompanying drawings, forming a part hereof, and wherein is disclosed, for the purpose of illustration, a convenient and satisfactory embodiment thereof.

In the drawings:

Figure 1 is an elevation of an apparatus of the character referred to, partly broken away, and partly in section, thereby illustrating the interior construction;

Figure 2 is a transverse section;

Figure 3 is a similar section illustrating the apparatus in action;

Figure 4 is a detail perspective view enlarged of a portion of the conveyor and breaker means.

Like reference numerals refer to corresponding parts throughout the several views, in which 1 are suitable legs or supports adapted to rest on a surface and to receive a rotatable drive shaft 2. This shaft is adapted to be rotated at a high rate of speed, in any desired manner, but preferably through the medium of a relatively large driving pulley 2^a rotated from any suitable source, and adapted to impart movement to an endless belt 4 positioned on a relatively small pulley 3, secured to the shaft 2. Suitable supports 6 are provided for the stationary parts of the apparatus, which include a suitable cylindrical drum 5 conveniently open at opposite ends, as illustrated at 7. These openings are preferably elliptical, the walls 7^a surrounding the openings 110

projecting inwardly from the end wall of the drum and having an outwardly projecting flange 7^a extending substantially parallel with the end wall of the drum.

- 5 The particular construction and arrangement of these parts prevents any of the material from finding a way out through the openings by flowing over the wall surrounding the same, and the particular slope of 10 the surrounding wall of the openings assists in feeding the material to the base of the drum to be taken up by the conveyors and breakers presently to be described.

It will be noted that the openings are eccentrically arranged, whereby the lower portion thereof will be positioned a considerable distance above the base of the drum, thereby preventing any splashing of the material at the ends of the drum through said opening. A sleeve or jacket 8 surrounds the drum and is suitably connected thereto so as to provide an intervening space 9 for the reception of the material to give the necessary temperature to the drum surface.

- 25 Supported on the shaft 2 is a suitable rotary breaker and conveyor mechanism, preferably made up as follows:—

Spokes or webs 10 are secured at intervals on the shaft 2, three sets being illustrated. 30 Projecting between the webs 10 are elongated longitudinally extending brace bars 12, upon which are mounted annular rings or rims 11. The rims 11 are secured to the ends of the bars 12, through the medium of 35 securing bolts 12^a, which latter also form securing means for connecting the ends of the bars 12 to opposite ends 10^a of the webs 10. Arranged at suitable intervals about the periphery of the wheel, formed by the parts 40 just described are conveyor members preferably comprising angle bars 13, secured to flanges 11^a of the rims 11, in any desired manner as by rivets 13^a. The flanges 14 of the angle bars are adapted, in the rotary 45 movement of the device, to pick up and carry the material to and around the inner surface of the drum. The conveyor members preferably extend from end to end of the breaker and conveyor mechanism.

- 50 Arranged to extend between the flanges 11^a of the annular rim members 11, and at closely associated distances apart, are suitable chains 15, such chains being connected in any desired manner, as for instance, as 55 illustrated in Figure 4, wherein one of the links of the chain terminates in a suitable threaded bolt 15 adapted to receive a securing nut 15^b engaging the outer surface of the rim 11^a. This connection affords 60 means whereby the chains may, at all times, be maintained taut. The chains are substantially flush with the outer edge of the flange 14 of the conveyor members proper, and cooperates with said conveyor members 65 to lift the liquid or substance and impart

a rotary movement thereto, the chains further serving to break up the material into relatively fine particles, making it easier or more direct for the gases or vapors to pass through the liquid or substance, which will 70 take the form of a film or layer on the inner periphery of the drum. Suitable means for exteriorly heating the drum preferably takes the form of steam or the like, which enters the space formed between the jacket 75 8 and the periphery of the drum 5. A suitable piping 17 connecting with the jacket, preferably at the top, affords means for the introduction of the steam which encircles the drum and fills the space between the 80 drum and jacket.

It is obvious, of course, that material, other than steam may be introduced into said space, according to the desired treatment, and the flow may be regulated or 85 shut off at will, through the medium of a suitable valve 17^a introduced in said pipe. It has been found that the evaporating process may be accelerated by the introduction, at suitable intervals, into the drum of air 90 or steam, or both, according to conditions. This is preferably accomplished through the medium of piping, projecting through the jacket. For the purpose of illustration, I have shown two pipes 18 for steam, the latter being adapted to receive the steam from any suitable source, preferably through the medium of intake pipes 21. The admission of steam may be regulated or entirely shut off through the medium of valves 21^a interposed in the piping 21. The upper pipe 21 may be closed, at its opposite end, as illustrated, or provided with an outlet connection similar to the connection 21^b for the lower pipe 18, having a valve 21^c for the 105 discharge of any water of condensation in the piping, and also to provide a discharge means from the interior of the drum for cleaning purposes.

The air pipes, two also being shown for 110 illustration, are indicated by the numerals 19, these pipes being preferably closed at one end, and having valves similar to the valves 21^a heretofore referred to, for controlling or cutting off the supply of air.

115 It is to be understood that the air and steam pipes may be otherwise arranged than illustrated and described, and that any desired number or relative arrangement of each may be employed, according to conditions. All of the pipes have suitable outlet ports 20, leading through openings in the periphery of the drum. The members 20 preferably take the form of nipples, and are constructed to provide offset outlets projecting in the general direction of rotation of the breaker and conveyor mechanism, to the end that the air or steam, or both, will be introduced by an entraining action, due to the movement of the fluid or substance 125 130

about the inner surface of the drum. The air or steam passes through the film or layer of fluid or substance thereby assisting in abstracting the moisture therefrom.

5 Other material or gases in lieu of or in addition to air or steam may be utilized, and any one or all of the pipes may be closed at will by suitable valves 21^a. The nipples are conveniently welded to the wall surrounding the openings so as to form an air tight joint at this point.

A suitable valve controlled discharge outlet 21^b leads from the space between the drum 5 and jacket 8 for the discharge of 15 any water of condensation necessary.

The milk or material to be treated is preferably introduced through one end of the drum through the medium of a pipe or chute 22 projecting through the end wall of the 20 drum, and having an outlet at a point to discharge into one of the runways formed by the flanges 7^a, 7^b, surrounding the end opening of the drum. The treated fluid or substance may be removed at any convenient 25 point about the periphery of the drum, and as illustrated an outlet port 23 may be provided in the drum, and connected with a tangentially arranged pipe or flue 24, adapted to discharge into a suitable trough 30 or runway 25, or into other containers, should it be desired to employ a multiple treating apparatus. The outlet tube 24 is 35 preferably arranged at that end of the drum opposite to the inlet 21, and the treated material will, of its own motion, in moving about the inner surface of the drum, find an outlet through the pipe 24.

The operation of the apparatus may be reviewed as follows:—

40 Assuming that the liquid to be treated by the apparatus is milk, the same is fed into the drum conveniently at one end. The breaker and conveyor mechanism having been set in motion, through the medium of pulleys 2^a—3, belt 4, and shaft 2, will travel at a high rate of speed say from 200 to 250 revolutions per minute (speed being altered according to conditions). The material is immediately cut up by the conveyors, and 45 owing to the rapid movement thereof, is transferred to the heated sides of the drum and deposited thereon. The flow of material continuing, the deposit on the surface is continued, until there is built up on the surface, 50 through the centrifugal action, a stratum or layer of material varying in thickness or depth up to from 2 to 5 inches according to the rapidity of the movement of the conveyors. The operation of the parts is such 55 that the material is not allowed to settle, but, as stated, accumulates and has a movement over the surface in a forward direction. It has been observed that the movement of the material in its circular course 60 over the heated surface is somewhat likened 65 to that of a wheel rim when in motion. It has also been ascertained that the speed of the moving body of material approximates four-fifths of the speed of the conveyors. By the relative lagging movement of the 70 material, and by the employment of the chains, the material is subjected to a breaking-up action which greatly facilitates and accelerates the evaporation, in that the molecules or particles are separated and the 75 gases arising are more quickly liberated and permitted to enter the quiet zone within the moving ring of material. The milk or liquid being carried up, and deposited by the mechanism described, has a tendency to increase in thickness so that the inner face of the ring shaped body of liquid presents a perfectly smooth surface throughout, as distinguished from a broken-up or ruffled surface. The conveyors are arranged conveniently within about one-half of an inch of the drum surface, and maintain the liquid properly therebeyond in position and in contact adjacent the heated surface by the 80 centrifugal force created, while the outer 85 surface or portion of the liquid belt, as above stated, is maintained in position by the centrifugal action, as I understand, and possibly, also, by the suction action of the more rapidly moving conveyors and the natural 90 entraining action of the material itself. The relatively fast movement of the conveyors maintains the orbital action of the moving material so that the liquid is maintained in close and forcible contact with or in proximity to the heating surface. The heated 95 gases and vapors generated at or adjacent the surface being lighter than the liquid, will pass off therethrough, carrying with them moisture, and finding exit through the quiet 100 zone at the center of the drum. These 105 vapors may be allowed to escape into the air or may be collected or abstracted and conducted to other separators of a character to perform a multiple treatment of the material. 110

During the continuous operation of the machine, the milk being fed in at one end is automatically and continuously discharged at the other end in a concentrated or semi-liquid form. The operation of the apparatus is such that the milk at no times settles at the bottom, and the abstraction can occur at any convenient point about the periphery of the drum.

Excellent results have been obtained with 120 a drum having imperforate walls, but the operation may be accelerated somewhat by the introduction of the air and steam pipes referred to, the air or steam, or both, being introduced into the drum and through the 125 body of liquid or substance preferably by an entraining action due to the arrangement of the nipples 20, and the fluid in its passage abstracting moisture from the material and entering the quiet zone. Where it is desired 130

to subject the volume of material to the action of steam alone, for the usual treatment of the milk constituents, such as casein, it is only necessary to move the air pipe valves to 5 closing position.

While in describing the operation of the apparatus, milk has been referred to as the material being treated, it is to be understood that the apparatus is equally susceptible for 10 use and adaptation in other connections and for the treatment of other materials.

The condensed fluid or treated material is, at the end of the treatment, taken out from the container through a relatively small escape 15 passage, while the large volumes of vapor and gas that are withdrawn or separated from the material are being simultaneously taken out through corresponding larger or more copious passage-ways from 20 the interior of the container. The area of the vapor escape opening at 7 is made as large as practicable in relation to the cross area of the vapor receiving central zone within the container. It cannot to advantage 25 be made of a fully equal area, because of the liability of chilling the interior chamber, wherein it is desired to maintain a constant uniform temperature in the neighborhood of the film or fluid. But the areas of 30 the fluid discharge opening and of the vapor discharge opening are related, in their dimensions, to the volumes respectively of materials passing through them. It is desirable to insulate or separate the passage 35 for the treated material from the vapor escape opening to prevent re-condensation of vapor; and as shown, the treated fluid material is withdrawn at the end of its path directly from the film through a tangentially 40 arranged duct while large volumes of vapor pass beyond the transverse planes of this duct and escape through the large discharge opening.

I have in other copending applications illustrated and described modified forms of 45 evaporating or condensing apparatus, and novel methods of procedure in evaporating or condensing milk, and in this connection reference is made to the application Serial 50 No. 797,087, filed October 23, 1913, renewed as Serial No. 108,956, relating to a method, and of which said application the present application is a division, and reference is further made to the following applications:—718,114, filed August 31, 1912; 55 738,178 filed December 23, 1912; 277,904 (a division of 718,114, filed February 18, 1919; 40,757, filed July 19, 1915; 77,996, filed February 12, 1916; and I reserve the right to 60 claim in my copending applications the novel subjects-matter therein disclosed and not herein claimed.

An additional feature of the apparatus resides in the fact that by the use thereof, I

am enabled to eliminate the customary entrainment of a considerable portion of the solids which under existing practices, where the substances are not subjected to pressure during evaporation, would be carried off with the gases and vapors emanating from the body of substance. By my invention, owing to the rapid rotary movement provided by the conveyors, and breaker mechanism, the continuous centrifugal force to which the substance is constantly subjected would prevent any portion of the solids being entrained and lost with the discharged vapors and gases.

The drum is shown and described as having open ends, and it is to be understood that such a construction is advantageous when the machine is employed for the treatment of milk and other substances. Should, however, the machine be employed for evaporating water, obviously, changes can be made with reference to the size of the openings.

Other changes may be made in the machine without departing from the general principles thereof, and still come well within the spirit of the invention.

I claim:—

1. In an evaporating apparatus, the combination of a cylindrical container, rotary conveyor means within the container adjacent to the wall thereof and adapted to move the material in a circular path over said wall and maintain the same in contact with the wall, and means for supplying treating fluid to the interior of the container in the direction of movement of the conveyor mechanism.

2. In an evaporating apparatus, the combination of a cylindrical container, rotary conveyor means within the container adjacent to the wall thereof and adapted to move the material in a circular path over said wall and maintain the same in contact with the wall, a pipe arranged to supply treating fluid, said pipe having a series of inlet ports at the periphery of the cylinder and adapted to discharge tangentially into the interior of the cylinder.

3. In an evaporating apparatus, the combination of a cylindrical container, rotary conveyor means within the container adjacent to the wall thereof and adapted to move the material in a circular path over said wall and maintain the same in contact with the wall, a pipe arranged to supply treating fluid, said pipe having a series of inlet ports at the periphery of the cylinder adapted to discharge tangentially into the interior of the cylinder, and means exteriorly of the cylinder for regulating the temperature of the wall thereof.

4. In an evaporating apparatus, the combination of a stationary cylindrical con-

- tainer, conveyor means within the container adapted to rotate in close proximity to the wall of the container to apply the material to the wall of the container and maintain to the wall of the container and maintain 5 the same in contact therewith, means for regulating the temperature of the wall of the container, and a plurality of conduits adapted to contain treating fluids, said conduits being arranged adjacent the periphery 10 of the cylinder and having a plurality of outlets opening through the periphery of the cylinder, and means for regulating the supply of fluid through either or both of said conduits.
- 15 5. In an evaporating apparatus, the combination of a stationary cylindrical container, conveyor means within the container adapted to rotate in close proximity to the wall of the container to apply the material to the wall of the container, and maintain 20 the same in contact therewith, means for regulating the temperature of the wall of the container, and a plurality of conduits adapted to contain treating fluids, said conduits being arranged adjacent the periphery 25 of the cylinder and having a plurality of outlets opening through the periphery of the cylinder, and means for shutting off the supply of material through either one or 30 both of said conduits.
- 35 6. In an evaporating apparatus, the combination of a stationary cylindrical container, open at one end, a collar surrounding the opening forming an interior runway, means for introducing material to be treated 40 into the runway of the collar, and rotary conveyor mechanism positioned within the container.
- 45 7. In an evaporating apparatus, the combination of a stationary cylindrical container, open at one end, a collar surrounding the opening forming an interior runway, means for introducing the material to be treated 50 into the runway of the collar, said opening being eccentrically arranged relative to the end of the container and overlying the central portion of the container, and rotary conveyor mechanism positioned within the container.
- 55 8. In an evaporating apparatus, the combination of a substantially cylindrical container having an inlet adjacent one end and an outlet adjacent the opposite end for the material to be treated, and conveyor means 60 within the container including an elongated chain extending longitudinally of the container adjacent the surface thereof, and means for rotating said conveyor means at a high speed whereby the material will be 65 maintained in film formation while continuously moved from the inlet to the outlet end of the container, and simultaneously circularly over the surface of the container, and means for subjecting the surface of the 65 container to heat.
9. In an evaporating apparatus, the combination of a cylinder having an inlet and outlet for the material to be treated, and conveyor mechanism comprising a rotary shaft, a series of angle bars concentrically 70 arranged about said shaft extending longitudinally of the container and adjacent the inner periphery thereof, and a series of breaker chains also supported from the shaft and extending longitudinally of the 75 container.
10. In an evaporating apparatus, the combination of a cylindrical container, means for subjecting the surface thereof to a temperature different from that of the material 80 to be treated, and conveyor and breaker mechanism arranged within the container comprising a shaft mounted for rotation, webs projecting from the shaft, conveyor mechanism projecting between the webs and 85 having outstanding bars, and chains arranged between the bars extending longitudinally thereof and supported by said webs.
11. In an evaporating apparatus, the combination of a cylindrical container, a jacket therefor, means for introducing steam into the space between the container and jacket, means for introducing steam or the like through the wall of the container to the 90 inner surface thereof, and means for conveying the material into contact with said surface while being continuously moved thereover, said means including a rotatable shaft and a conveyor drum supported on the 100 shaft, said drum having a series of angle bars projecting longitudinally of the container, and a series of chains also extending longitudinally of the container, and means for rotating said conveyor drum at a high 105 rate of speed.
12. In an evaporating apparatus, the combination of a horizontally disposed stationary cylindrical container, a steam jacket surrounding the same, said container being 110 open at opposite ends, and conveyor and breaker mechanism positioned within the container comprising a skeleton drum having a circumferential series of chains.
13. In an evaporating apparatus, the combination of a horizontally disposed stationary cylindrical container, a steam jacket surrounding the same, said container being 115 open at opposite ends, and conveyor and breaker mechanism positioned within the 120 container comprising a skeleton drum having a circumferential series of angle bars and chains extending horizontally.
14. In an evaporating apparatus, the combination of a horizontally disposed cylinder 125 open at opposite ends for the escape of vapor, means for regulating the temperature of the wall thereof, and connected mechanism for applying and maintaining under movement a continuous layer of material to 130

be treated on and over the cylindrical surface, and for maintaining a central quiet zone within said layer, said cylinder having an opening permitting the discharge of the treated material independent of the vapors.

15. In an evaporating apparatus, the combination of a horizontally disposed cylinder having a surrounding heating chamber and a relatively small discharge passage for the treated material, means for introducing into said chamber heat sufficient to vaporize liquid constituents of the material to be treated, a rotatable shaft within the cylinder, connected conveyor mechanism mounted on the shaft, and means for rotating said shaft at a high rate of speed whereby the material will be applied by said mechanism in continuous layer formation to the surface of the container, and subjected to continuous uninterrupted movement in the same general direction over said surface, said mechanism also operating to maintain a central quiet zone within said layer of material, and said container having an opening for the free escape of vapors from said central quiet zone, said discharge passage and said vapor escape opening having areas corresponding to the volumes of the treated material and of the vapor withdrawn therefrom.

16. In an evaporating apparatus, the combination of a stationary horizontally disposed cylindrical container having a centrally arranged opening at opposite ends of a size sufficient to permit of the copious discharge of vapors, conveyor means within the container adapted to rotate in close proximity to the wall of the container, and to apply the material to the wall of the container and maintain the same, while under movement, in cylindrical formation in contact with said wall of the container, said conveyor means also operating to maintain a central quiet zone within the container, and means for regulating the temperature of the wall of the container.

17. In an evaporating apparatus, the combination of a stationary horizontally disposed cylindrical container, conveyor means within the container adapted to rotate in close proximity to the wall of the container and to apply the material to the wall of the container and maintain the same under movement in continuous cylindrical layer formation in contact with the container, said container being open in communication with the central zone formed by the cylindrical layer of material whereby to maintain the pressure within the container at substantially atmospheric pressure and whereby to permit of the copious discharge of the accumulating vapors from the container, means for regulating the temperature of the wall of the container, means for introducing the material to be treated to the container

adjacent one end, and a tangentially disposed outlet flue connecting with the periphery of the container adjacent the opposite end thereof.

18. In an apparatus for evaporating liquid constituents of materials, the combination with a container of circular section having end walls one of which is provided with a vapor escape of substantial area, means for introducing the material at one end and means adjacent the periphery of the container for permitting the removal of the material after treatment, inwardly projecting flanges on the end walls positioned adjacent the outer edge thereof adapted to prevent material from moving over the end wall, means for heating the circular walls of the container and rotary instrumentalities located within the container for forcibly projecting material onto the heated walls causing the same to circulate thereover and to move longitudinally thereof from the point of introduction.

19. In an evaporating apparatus, the combination of a horizontally disposed cylindrical container, external means for heating the surface of the container, means whereby a continuous circular layer of the material is maintained in contact with the treating surface and subjected to continuous uninterrupted circumferential and simultaneous endwise movement over said surface, said container having an inlet for the material at one end and an outlet for the material at its opposite end, means for maintaining substantially atmospheric pressure within the container and for permitting unrestricted rapid discharge of the accumulating vapors from the central zone formed by the moving layer of material.

20. In an apparatus for treating substances containing liquid to change the consistency thereof comprising a container of circular cross section, means for subjecting the outer wall of the container to a high heat sufficient to vaporize liquid constituents of the material whereby the inner surface thereof constitutes a heated treating surface, means for introducing the material at one end of the container, a discharge passage of relatively small area near the opposite end of the container for the escape of the treated material, conveyor means within the container extending longitudinally thereof adjacent the treating surface, and means for rotating said conveyor means at a high speed, said parts being constructed and arranged whereby the material will assume the form of a thin layer on the treating surface of substantially uniform thickness throughout, and whereby said layer is caused to move circularly and lengthwise towards the discharge over the surface at rapid speed while a central quiet zone is maintained within the layer for the escape

inwardly of gases and vapors, and said container having a relatively large central opening for the free discharge of said gases and vapors from the container, said discharge opening for treated material and said vapor discharge opening having areas approximately related to the volume of escaping treated material and the volume of the vapors withdrawn therefrom.

21. In an evaporating apparatus the combination of a container having a circular cross section, exterior heating means for the container for imparting to the wall thereof a high degree of temperature sufficient to vaporize liquid constituents of the material to be treated, said container having an inlet adjacent one end and a relatively small outlet adjacent the opposite end, and interior means for spreading a thin uniformly distributed layer of the substance on the heated wall of the container and for causing a rapid circulation of the substance circumferentially and lengthwise over said heated wall, and said container having a relatively large central outlet whereby to maintain the container at substantially atmospheric pressure and permitting the vapors and gases to escape from the substance and from the container during treatment, the areas of the said vapor outlet for treated material and the said vapor outlet being related as are the volume of escaping treated material and the volume of the vapor withdrawn therefrom.

22. In an apparatus for treating a substance containing a liquid to change the consistency, the combination of a cylindrical container, means exteriorly of the container for applying to the wall thereof a temperature different from that of the material under treatment, said container having an inlet adjacent one end and an outlet of relatively small area adjacent the opposite end for the escape of treated material, and means for causing the material to form in a continuous layer formation rapidly movable over the inner surface of the container, said means including longitudinally extending flexible members spaced circumferentially and extending longitudinally of the container adjacent the inner surface thereof, and said container having a relatively large central outlet for the escape of vapors from the zone within the layer of material, the areas of said outlet for treated material and of said vapor escape outlet being related approximately as are the volume of escaping material and the volume of the vapor withdrawn therefrom.

23. In an evaporating apparatus the combination of a substantially circular treating surface, means for applying to said surface a temperature different from that of the material to be treated, means for introducing the material adjacent one end of said surface and allowing the treated material to es-

cape adjacent the opposite end thereof, rotatable means movable adjacent said surface for causing a circular layer of said material to move over said surface, and means for introducing a fluid to the outer surface of said material.

24. In an evaporating apparatus, the combination of a cylinder having a central copious opening at one end for the free escape of vapor, means for regulating the temperature of the wall thereof, and connected mechanism for applying and maintaining under movement a continuous layer of material to be treated on and over the cylindrical surface, and for maintaining a central quiet zone within said layer, said cylinder having a relatively small opening permitting the discharge of the treated material independent of the vapors, the area of the discharge opening for the treated material being related to that of the vapor escape opening approximately as is the volume of discharged material to the volume of the vapor withdrawn therefrom.

25. In an evaporating apparatus, the combination of a cylinder having a surrounding heating chamber, means for introducing into said chamber heat sufficient to vaporize liquid constituents of the material to be treated, a rotatable shaft within the cylinder, connected conveyor mechanism mounted on the shaft, and means for rotating said shaft at a high rate of speed whereby the material will be applied by said mechanism in continuous layer formation to the surface of the container, and subjected to continuous uninterrupted movement in the same general direction over said surface, said mechanism also operating to maintain a central quiet zone within said layer of material, and said container having a copious discharge opening for the free escape of vapors from said central quiet zone, and a relatively smaller discharge opening for the treated material separated from the relatively large vapor escape opening whereby the treated material and the vapors will be withdrawn from the container in differing volumes corresponding to the areas of the said openings.

26. In an evaporating apparatus, the combination of a cylindrical container, means for imparting to the surface of the container a temperature different from that of the material to be treated, and means whereby a continuous circular layer of the material is maintained in contact with the treating surface and subjected to continuous uninterrupted circumferential and simultaneous endwise movement over said surface to the point of discharge, and means for maintaining substantially atmospheric pressure within the container, and permitting the unrestricted rapid discharge of accumulating vapors directly from the central vapor space formed by said circular layer of material.

27. In an evaporating apparatus, the combination with a horizontally disposed container of circular cross section having an inlet for the material adjacent one end, and an outlet for the treated material adjacent the opposite end, and said container also having in one end a relatively large opening for the free and quick escape of vapors from the container, inwardly projecting circular flanges on the ends positioned outwardly beyond the plane of the vapor outlet, means for heating the container walls and rotating means located within the container and extending substantially from end to end thereof for shaping the material to the walls of the container, said means arranged to engage the material as it enters the container to cause the same to move circularly over the heated surface and longitudinally thereof towards the outlet substantially as described.

28. In an evaporating apparatus, the combination with a container of circular cross-section having at its ends an opening to the atmosphere for the free escape of vapors, means for introducing the material at one end of the container, means for removing the material at the other end of the container, means for heating the container and means for causing the body of the material as introduced to be spread onto the curved inner surface of the container and moved bodily

from the point of introduction circularly over the surface and longitudinally to the point of escape.

29. In an evaporating apparatus for material containing liquid, the combination of a tubular container having an operating surface circular in cross-section, said container having adjacent one end an inlet for vaporizable material, and an outlet adjacent its opposite end for the treated material, means for heating the wall of the container, and means continuously rotating rapidly adjacent the treating surface for positively engaging the material for forcing it radially outward and cooperating with the container to force the material circularly and longitudinally of the axis of the container to its point of discharge, said means being constructed and arranged to maintain an approximately hollow cylindrical stratum of the material in contact with the surface and having a quiet central zone, and said container having a relatively large opening adjacent one end for the copious discharge of vapors from the central zone.

In testimony whereof I affix my signature in presence of two witnesses.

CHARLES R. MABEE.
